(57) **CLAIM**

We claim the ornamental design for a sandwich, as shown and described.

DESCRIPTION

FIG. 1 is a front/top perspective view of a first embodiment of a sandwich (no ripples on the crimp);

FIG. 2 is a top plan view thereof;

FIG. 3 is a bottom plan view thereof;

FIG. 4 is a front elevational view thereof;

FIG. 5 is a rear elevational view thereof, for which a front side elevational view would be a mirror image thereof; and FIG. 6 is a left side elevational view thereof, for which a right side elevational view would be a mirror thereof.

FIG. 7 is a front/top perspective view of a second embodiment of the sandwich (stippled; no ripples on the crimp);

FIG. 8 is a top plan view thereof;

FIG. 9 is a bottom plan view thereof;

FIG. 10 is a front elevational view thereof;

FIG. 11 is a rear elevational view thereof, for which a front side elevational view would be a mirror image thereof; and, FIG. 12 is a left side elevational view thereof, for which a right side elevational view would be a mirror image thereof.

The stippling in FIGS. 7–12 represents a contrast in appearance between the second embodiment of the sandwich and the first embodiment of the sandwich shown in FIGS. 1–6, FIGS. 1–6 are identical to FIGS. 7–12 except for the stippling. The broken lines immediately adjacent the shaded areas represent the bounds of the claimed design, while all other broken lines are directed to environment; the broken lines form no part of the claimed design.
